UNITED STATES PATENT OFFICE.

GEORGE SAMUEL BOYLER, OF TORONTO, ONTARIO, CANADA.

LOCOMOTIVE DRAFT CHAMBER.

Application filed April 28, 1924. Serial No. 709,657.

To all whom it may concern:

Be it known that I, George SAMUEL BOYLER, a subject of the King of Great Britain, and a resident of the city of Toronto, in the county of York, in the Province of Ontario, Canada, have invented certain new and useful Improvements in Locomotive Draft Chambers, of which the following is the specification.

10 My invention relates to improvements in locomotive draft chambers, and the object of the invention is to provide a construction of chamber which may be very quickly and easily assembled or disassembled, thereby greatly economizing the time, labour and cost of repair to this part of a locomotive and yet at the same time providing a structure which is rigid, tight fitting and strong, and it consists essentially of the arrangement and construction of parts hereinafter more particularly explained.

Fig. 1 is a longitudinal sectional view through a portion of a locomotive and my draft chamber.

25 Fig. 2 is a sectional plan view of a portion of a locomotive and my draft chamber.

Fig. 3 is a perspective detail showing the forward end of my draft chamber located in position within a portion of the body of a locomotive.

30 Fig. 4 is a sectional perspective view taken through the body of a locomotive and the draft chamber intermediately of its length, and showing the rear wall structure of the draft chamber.

Fig. 5 is a cross sectional view through the locomotive taken on line 5—5, Fig. 2.

Fig. 6 is a cross sectional view similar to Fig. 5, taken on line 6—6, Fig. 2.

40 Fig. 7 is a sectional detail of my key securing device.

In the drawings like characters of reference indicate corresponding parts in each figure.

45 1 indicates the body of a locomotive provided with the usual exhaust nozzle 2 located directly beneath the smoke stack 3.

4 is the front head of the boiler, from which extends the flues 5 containing the usual super-heating coils 6 extending from the header 7.

8 is a steam supply pipe leading to the nozzle 2. 9 is a stationary dead plate extending transversely of the upper portion

of the locomotive body and provided with a rectangular orifice 9 $\frac{1}{2}$, the upper edge of which is turned rearwardly and upwardly to form a transverse groove, as indicated at 9 $\frac{1}{2}$.

50 10 is a removable dead plate the upper portion of which is turned so as to form a transverse inverted groove portion, as indicated at 10 $\frac{1}{2}$, the edge portion 10 $\frac{1}{2}$ of which fits into the groove 9 $\frac{1}{2}$ of the stationary dead plate 9.

55 The lateral vertical edges of the removable dead plate 10 are provided with extensions 11 which are off-set rearwardly, as indicated at 12, see Fig. 2, so as to fit against the forward face of the stationary dead plate 9 at each side of the orifice 9 $\frac{1}{2}$, the body of the dead plate 10 projecting through such orifice by means of the off-set portions 12.

60 The lower edge of the removable dead plate 10 is rolled up to form a transverse groove portion 13.

65 14 and 15 are guide plates secured to the internal face of the wall of the locomotive body to form a longitudinally extending guide-way 16. The stationary dead plate 9 and the removable dead plate 10 form the rear wall of my smoke chamber.

70 I will now describe the structure by which the floor of the smoke chamber is formed.

75 17, 18 and 19 are three dead plates forming sections of a floor plate which are fitted together as hereinafter described, to form the floor of my draft chamber.

80 The central plate 17 is provided with upwardly off-set portions 20 and 21 which overlie the inner edges of the side dead plates 18 and 19, the body of the dead plate 17 being in horizontal alignment with the bodies of the dead plates 18 and 19 and fitting between the inner opposing edges of the dead plates 18 and 19.

85 The off-set portions 20 and 21 are provided with longitudinal slots 22 and 23 through which extend loop portions 24 and 25 which are secured to or form part of the side dead plates 18 and 19. These loop portions 24 and 25 project upwardly above the surface of the off-set portions 20 and 21 so as to receive wedging keys 26 and 27. By this means the dead plates 17, 18 and 19 are securely locked together to form a unitary floor structure.

90 The rear edges of the dead plates 17, 18

and 19 are turned up, as indicated at 17^x, 18^x and 19^x to form inverted loop portions 28 adapted to receive the upwardly extending edge of the transverse groove portion 13.

5 The downwardly extending portion of the loop 28 is turned upward to form a transverse groove portion 29 fitting snugly within the groove portion 13. The upper guide plates 14 are provided at their forward ends 10 with forwardly extending downwardly directed hook loops 30 set in an opposite direction to the transverse groove portion 29.

15 31 is a rod which fits within the transverse groove portion 29 so as to extend across the rear end of the smoke chamber and fit at its ends within the hook portions 30.

20 It will be understood that the lower portion of the stationary dead plate 9 is formed so as to have a certain amount of spring, and that the space between such dead plate 25 and the hook portions 30 is less than the diameter of the rod 31. It will therefore be seen that in order to force the rod 31 into position, it is necessary to force the ends of such rod between the hook portions 30 and the dead plate 9, which dead plate yields in order to permit the rod to pass into engagement with the hook portions 30, and thus lock the rod in position. By this means it 30 will be seen that the dead plates 17, 18 and 19 forming the floor of the smoke chamber are securely locked to the removable dead plate 10.

35 The forward wall of my smoke chamber is formed, as is common in all draft chambers, by a spark arrester. My spark arrester, however, is constructed as follows:—

40 In diametrically opposite positions in the wall of the locomotive body are formed longitudinally extending slotted openings 32, see Figs. 2 and 7.

45 33 is a rod which extends transversely of the locomotive body and through the slotted openings 32, projecting outward from each side of the locomotive body. The dead plate 17 is provided with a pair of loops 34 and 35 at its forward end through which the rod 33 extends. The dead plates 18 and 19 are each provided with loops 36 and 37 50 through which the rod 33 also extends.

38, 39 and 40 are screen frames, each provided with screening 41 so as to prevent the passage of sparks.

42 and 43 are flange members secured to 55 the upper portion of the locomotive body, such flanges being inclined inwardly towards their lower ends. The lower portion of the flange 43 is separated at each end from the wall of the locomotive body as indicated at 44, so as to permit a certain amount of spring to this portion of the wall when the parts are secured together, as will hereafter appear.

60 The central portion of the flange 42 is off-set slightly outward, as indicated at 45

so as to receive the central frame 38 and the over-lapping portions of the side frames 39 and 40, as indicated in Fig. 3. The side portions of the frame 38 are provided with longitudinal slots 38^x through which loops 70 46 extend, such loops being secured to or forming part of the overlapping portions of the side frames 39 and 40.

75 47 are keys which extend through such loops so as to securely hold the frame members together. The lower edge of the central frame member 38 is provided with loop portions 48 and 49 through which the rod 33 extends.

80 Each side frame 39 and 40 is provided with loop portions 50 and 51 through which the rod 33 also extends. By means of the rod 33 it will be clearly seen that the lower edges of the frames 38, 39 and 40 are securely connected to the forward edges of the 85 dead plates 17, 18 and 19 forming the floor of the smoke chamber. 52 are hollow bosses which extend outwardly from the body of the locomotive and into which the projecting ends of the rod 33 extend. The bosses 90 52 are provided with rearward extensions 53 provided with a key orifice 54, a portion of such orifice extending through the open centre of the boss 52, as clearly indicated in Fig. 7. 95

55 5 is a wedge key which is driven through the orifice 54 with its forward edge in engagement with the projecting end of the rod 33, and thereby, as the key is driven, such rod is forced forward at each end, the 100 screen frames 38, 39 and 40 being permitted to move slightly forward by reason of the spring portion 44 of the flange 43. Also a forward draw is exerted upon the dead plates 17, 18 and 19 and their interlocking connection with removable dead plate 10 of the 105 rear wall of the smoke chamber. By means of this draw the removable dead plate 10 is drawn forward at its lower end, the upper edge fulcruming in the groove 9^x 110 thereby drawing the lateral extensions 11 into tight contact with the rear face of the stationary dead plate 9 at each side of the orifice 9^x, such dead plate being sprung slightly forward and thereby forming a 115 tight connection between the dead plate 10 and dead plate 9.

120 As will be clearly seen on referring to Fig. 2, the movement of the central dead plate 17 is permitted in this direction by means of a slotted opening 56 through which the exhaust nozzle 2 extends, and the slotted openings 57 and 58 through which the securing bolts 59 and 60 extend, which securing bolts serve to secure the central dead plate 17 to the flange 2^x of the exhaust nozzle 2. 125

130 61 and 62 are two plates each provided with loops 63 and 64 by which the plates are swung upon the cross rod 33. The outer

ends of the plates 61 and 62 are curved so as to fit the internal surface of the locomotive body to hold the plates in a forwardly inclined position. The plates 61 and 62 5 form a baffle member to which is secured an adjustable plate 65 provided with slotted openings 66 through which securing bolts 67 extend.

From this description it will be seen that

- 10 I have devised a very simple structure which may be quickly and easily interlocked together to form the draft chamber of a locomotive, dispensing with the large quantity of bolts which are ordinarily used for securing the parts together, and which of course necessitates a large expenditure of time to remove or to place in position when assembling or disassembling the parts during the repair of the locomotive.
- 15 20 It will be readily understood that all the parts are divided into sections so that they are readily withdrawable or insertible through the ordinary man-hole formed in the front end of the locomotive body.
- 25 25 What I claim as my invention is:

1. In a draft chamber for locomotives, the combination with a locomotive body provided with a dead plate forming the rear wall of the smoke chamber, of a floor plate 30 forming the floor of the draft chamber, an interlocking connection between the rearward end of said floor plate and the rear wall dead plate, spark arresting screens forming the forward wall of the draft chamber, an interlocking connection between the lower end of the screens and the forward end of the floor plate of the draft chamber, and wedging means for forcing the lower end of the spark arrester and floor plate 40 and their interlocking connections forward so as to force them into tight contact.

2. In a draft chamber for locomotives, the combination with a locomotive body and a stationary dead plate forming the rear wall of the draft chamber, of a movable dead plate swung at its upper edge upon the stationary dead plate, a floor plate horizontally guided at each longitudinal edge in the locomotive body, an inter-engaging connection between the floor plate and the swinging dead plate, a spark arresting screen, means for detachably securing the screen in the forward end of the locomotive, an interlocking connection between the lower end 50 of the spark arresting screen and the floor plate, and wedging means for forcing the lower end of the spark arresting screen, floor plate and movable rear wall dead plate forward, carrying the interlocking connections into tight contact.

3. In a draft chamber for locomotives, the combination with a locomotive body and a dead plate extending transversely of the locomotive body and forming the rear wall 65 of the draft chamber and having a trans-

verse orifice therein, of a removable dead plate, a hinge connection between the upper edge of the removable dead plate and the stationary plate along the upper edge of the aforesaid orifice, lateral extensions extending from each end of the removable dead plate adapted to contact with the rear face of the stationary dead plate when the removable dead plate is swung forward, a floor plate horizontally guided in the locomotive body, an interlocking connection between the floor plate and the removable dead plate, a spark arresting screen detachably mounted in the forward end of the locomotive and adapted to spring forward 70 at its lower end, an interlocking connection between the lower end of the spark arresting screen and the floor plate, and wedging means co-acting with the interlocking connection between the spark arresting screen 75 and the floor plate forcing such parts forward and adapted to draw the connection between the floor plate and the movable rear wall dead plate into tight contact.

4. In a draft chamber for locomotives, the combination with a locomotive body and a stationary dead plate forming the rear wall of the draft chamber of the locomotive and having an orifice therein having its upper edge turned upward in hook form, a removable dead plate having its upper edge turned rearwardly in hook form to engage the hook portion of the stationary dead plate, lateral extensions off-set rearwardly from the body of the removable dead plate 100 to extend to the rear of the stationary dead plate at each side of the aforesaid orifice, a floor plate longitudinally guided at each edge on the locomotive body, an interlocking connection between the floor plate and the removable dead plate, a spark arresting screen 105 removably mounted in the forward end of the locomotive and adapted to spring forwardly at its lower end, an interlocking connection between the lower end of the spark arresting screen and the floor plate, and means co-operating with such interlocking connection for drawing the floor plate and parts connected thereto forwardly into tight contact.

5. In a draft chamber for locomotives, the combination with a locomotive body and rear dead plate forming the rear wall of the draft chamber, of a removable dead plate pivoted along its upper edge to the stationary dead plate and having its lower edge turned forward and upward to form a transverse groove portion, a floor plate longitudinally guided in the diametrically opposite walls of the locomotive having its rear edge turned upwardly and over the upwardly extending ends of the groove portion of the movable dead plate, and having its extreme rear portion fitting the groove portion of the movable dead plate, a cross-rod extending 120 125 130

through the groove formed by the rear portion of the floor plate and the lower end of the movable dead plate, means carried by the locomotive body at each end of the rod 5 for detachably engaging the same, a spark arresting screen carried by the locomotive body, a detachable connection between the spark arresting screen and the floor plate, and means for co-operating with such de- 10 tachable connection for forcing the floor plate and the interlocking connection formed by the cross rod and engaging parts of the floor plate and movable dead plate forward- 15 ly into tight engagement with the portions carried by the locomotive body at each end of the aforesaid rod.

6. In a locomotive, the combination with a locomotive body having diametrical longitudinal slotted openings in proximity to its 20 forward end, of a draft chamber comprising a dead plate at the inner end of the draft chamber, the lower portion of which is adapted to spring forward, dead plates forming the floor of the draft chamber, a 25 detachable connection between the floor dead plates and the dead plate forming the inner end of the draft chamber, guide ways extending from the locomotive body in which the side edges of the floor plates are 30 slidably held, a transverse rod extending through the diametrically slotted openings of the locomotive body so as to project from the body and to which the floor plates are connected, spark screens secured transversely 35 in the locomotive body and attached at their lower ends to the cross rod and wedging means outside of the locomotive body for forcing the cross rod forward to exert a draw on the floor plates and the rear wall 40 dead plate to which the floor plates are connected.

7. In a locomotive, the combination with a locomotive body having diametrically opposite slotted openings in proximity to its 45 forward end, of a draft chamber comprising a stationary dead plate extending transversely of the locomotive body and forming the rear walls of the draft chamber and having an orifice therein, a movable dead plate 50 pivotally mounted at its upper end along the upper edge of said opening, lateral ex- 55 tensions from the movable dead plate adapted to engage the rear face of the stationary dead plate at each side of the aforesaid orifice when the movable dead plate is drawn forward, dead plates forming the floor of the draft chamber, guideways extending from the locomotive body in which the lateral edges of the floor are longitudinally 60 movable, a transverse rod, holding means at each side of the locomotive body into which the ends of the transverse rod extend, detachable connecting means between the lower portion of the movable dead plate and the 65 transverse rod, detachable connecting means

between the floor plates and the transverse rod, a forward transverse rod extending through the slotted openings of the locomotive body, loops formed on the forward ends of the floor plates through which the forward transverse rod extends, a spark screen held in the forward end of the locomotive body and having loops at its lower edge through which the forward transverse rod extends, and wedging means engaging the 70 ends of the transverse rod projecting from the locomotive body adapted to force forward such rod and the parts connected thereto.

8. In a locomotive, the combination with a locomotive body having opposing slotted openings formed in the wall thereof, of a draft chamber located in the body, a transverse dead plate having an opening therein and forming a portion of the rear wall of the draft chamber, a movable dead plate fitting the aforesaid opening to complete said rear wall and pivotally mounted at its upper edge along the upper edge of the opening, lateral lugs extending from the movable dead plate to engage the rear face of the stationary dead plate, a channel portion forming the lower edge of the movable dead plate, dead plates forming the floor of the draft chamber guides carried by the wall of the locomotive body in which the outer longitudinal edges of said floor dead plates slide, a channelled extension at the rear edge of the floor dead plates fitting within the channel portion of the movable dead plate of the draft chamber rear wall, a transverse rod extending through the channel portions of the floor dead plates, stationary hook members carried by the locomotive body and engaging the ends of the aforesaid transverse rod to limit its forward movement, a rod extending transversely along the forward edge of the draft chamber floor and engaging with the dead plates forming such floor, hollow bosses carried by the locomotive body into which the ends of the last mentioned transverse rod extend, and wedging means extending through the hollow bosses and engaging the ends of the transverse rod to force the same in a forward direction.

9. In a locomotive, the combination with a locomotive body having opposing slotted openings formed in the wall thereof, of a draft chamber located in the body, a stationary transverse dead plate located in the locomotive body and having an opening therein, a movable dead plate pivotally mounted at its upper edge along the aforesaid opening, stop means limiting the forward pivotal movement of the movable dead plate, a channel portion formed at the lower edge of the movable dead plate, dead plates forming the draft chamber floor slidably mounted in the locomotive body, a channelled por-

tion forming the rear edge of the draft chamber floor and fitting the channel portion of the movable dead plate, and wedging means for drawing the draft chamber floor in a forward direction to draw the movable dead plate into close contact with the stationary dead plate to close the opening of the transverse dead plate, and screens forming the forward wall of the draft chamber and connected to the floor thereof so as to ¹⁰ permit the aforesaid movement of the draft chamber floor during the wedging operation.

GEORGE SAMUEL BOYLER.
